UNITED STATES PATENT OFFICE.

THOMAS WILBERFORCE OLD, OF MONTREAL, QUEBEC, CANADA, ASSIGNOR TO THE CARTER-CRUME COMPANY, LIMITED, OF NIAGARA FALLS, NEW YORK, A CORPORATION OF CANADA.

MANIFOLDING-PAD.

970,739.

Specification of Letters Patent. Patented Sept. 20, 1910.

Application filed July 3, 1906. Serial No. 324,607.

To all whom it may concern:

Be it known that I, THOMAS WILBERFORCE OLD, residing at Montreal, in the county of Hochelaga and Province of Quebec, Canada, have invented certain new and useful Improvements in Manifolding-Pads, of which the following is a full, clear, and exact description, such as will enable others skilled in the art to which it appertains to make and 10 use the same.

This invention relates to manifolding devices, and more particularly to pads, sales-books, and the like.

One of the objects of the invention is to 15 provide an efficient device of the above character which will be capable of convenient manipulation.

Another object is to provide a device of 20 the above nature of the manifolding type.

Other objects will be in part obvious and in part pointed out hereinafter.

The invention accordingly consists in the 25 features of construction, combinations of elements and arrangements of parts which will be exemplified in the device hereinafter described and the scope of the application of which will be indicated in the following claim.

In the accompanying drawings, wherein 30 is illustrated one of the various possible embodiments of my invention, Figure 1 is a view in perspective of the same; Fig. 2 is a similar view showing the manner of using the same.

Similar reference characters refer to similar parts throughout both views of the drawing.

Before describing my invention with regard to the structural features thereof, it 40 may be noted in the use of sales-books or devices of a like character by salesmen or clerks, a reduction in the time consumed in inscribing the necessary entries therein results in a gain in the efficiency of such sales-man or clerk, as he is thereby enabled to wait upon a larger number of customers and to give more time to the performance of his other duties. It is therefore essential in 45 gaining the above advantages, among others, that the number of parts comprising the book be reduced to a minimum and that such parts shall be so disposed as to permit of a convenient and ready manipulation. By 50 my invention, which I shall now explain 55 more in detail, it will be apparent that I

have attained the above and other desirable ends through the provision of a simple and cheaply manufactured structure.

Referring now to the drawing, wherein is shown one adaptation of my invention applied to a sales-book, 1 designates a pad comprising a plurality of series or sets of sheets secured together at the stub end of the pad, as by means of wire staples 2, which serve to hold the same against a relatively 60 rigid back 3, said staples also operating to secure to the face of the pad a cover portion 4.

Each of the sets of sheets comprises a sheet folded along a weakened line 5 into a plurality of leaf portions 6 and 7 respectively, normally lying one above the other as shown, which leaf portions may be scored or lined in any desired manner. Each of these sheets is preferably weakened as at 8 along a line adjacent the point where it is secured to the 75 stub to permit of a more ready detachment therefrom, and the end of the upwardly folded leaf portion 7 falls short of the end of leaf portion 6 and lies adjacent weakened line 8.

Extending from the stub end of the pad and likewise bound therein by staples 2 are permanent sheets 9, one sheet being provided for each set or series of folded leaf portions. These sheets are coated upon their 85 under surfaces (assuming the pad to be in the position shown) with a suitable transferring material 10 adapted to serve as a medium for transferring inscriptions upon leaf portions 6, the opposite sides of said 90 sheets being left clean to enable inscriptions to be transferred thereon, and, if desired, they may be scored or lined in a manner similar to the scoring or lining of leaf portions 6 and 7. One of sheets 9 is positioned 95 between each of the leaf portions 6 and 7 of each set, and an extra one 11 is secured to the face of the pad immediately underneath the cover portion 4, the purpose of which will be presently apparent. The method of use of this adaptation of my invention may now be understood. Assuming the parts to be in the position shown in Fig. 1, which shows an unused sales-book or pad, leaf portion 7 of the uppermost of the set of sheets is first slightly raised to enable the extra permanent sheet 11 to be inserted between the same and the coated or plain surface of sheet 9 of said set. The book is now 100 ready for use and inscriptions written upon 105 the surface of sheet 9. The book is now 110

leaf portion 7 will be transferred in duplicate by sheet 11 upon sheet 9 and in triplicate by sheet 9 upon sheet 6. Leaf portions 6 and 7 may now be detached from the stub 5 by tearing same along the weakened line 8, and then detached from each other by being torn apart along weakened line 5. Any desired disposition may be made of the detached parts, it being understood, of course, 10 that sheet 9, having a transferred inscription upon its plain surface, remains permanently connected with the stub.

The further method of use of the sales-book is clearly illustrated in Fig. 2, where- 15 in for convenience of description the several sets of sheets comprising the pad have been numbered consecutively and leaf portions 6 and 7 of the first set detached from the pad. It will be noted that the leaf portion 7 of 20 the second set is shown raised to permit the permanent sheet of the first set, which set in the preceding operation received a transferred inscription upon its plain surface, to be superimposed upon the corresponding 25 sheet 9 of said second set with its coated surface in contact with the plain surface of said sheet. Leaf portion 7 is then permitted to fall upon sheet 9 of the first set, when an inscription written on said leaf portion will 30 be transferred in duplicate upon the permanent sheet of the second set and in triplicate upon the lowermost leaf portion 6 thereof, in the manner above described. It will be noted that each of the permanent 35 sheets acts as an inscription-receiving medium and a transferring medium in its own set, and as a transferring medium only in the next succeeding set; and it will be further noted that, inasmuch as the plain sur- 40 face of leaf portion 7 lies in contact with the inscription-receiving surface of the permanent sheet of the preceding set, the inscriptions transferred thereon will not be marred, and the sheet will not be defaced 45 or otherwise injured. It will be understood, of course, that operations substantially as above described may be repeated upon each of the succeeding series in the book. It will accordingly be apparent that I have pro- 50 vided a device well adapted to attain the several ends and objects of my invention, and one which realizes, among others, all the advantages above set forth. It will be apparent also that the invention is suscepti- 55 ble of use in many relations other than in the one herein shown.

As many changes could be made in the above construction and many apparently widely different embodiments of my invention could be made without departing from the scope thereof, I intend that all matter contained in the above description or shown in the accompanying drawing shall be interpreted as illustrative and not in a limiting sense. 60

I desire it also to be understood that the language used in the following claim is intended to cover all of the generic and specific features of the invention herein- 70 described and all statements of the scope of the invention, which, as a matter of language, might be said to fall therebetween.

Having described my invention, what I claim as new and desire to secure by Letters Patent is: 75

In a manifolding device, a pad comprising a plurality of uncoated sheets each of which comprises two leaf portions folded one upon the other along a weakened line, one of the leaf portions of each of said sheets being 80 provided with an end portion to which it is joined along a weakened line whereby the sheet is detachable therefrom, and a plural- 85 ity of sheets having impression-receiving upper sides and provided with a coating of transferring material upon their under surfaces, said last mentioned sheets being dis- 90 posed in alternate relation with said first mentioned sheets and one of said second men- 95 tioned sheets lying interposed between the leaf portions of each of said first mentioned sheets whereby two uncoated leaf portions will be interposed between adjacent coated sheets, said end portions associated with the first mentioned sheets and said second men- 100 tioned sheets being secured together whereby said second mentioned sheets will be per- 105 manently secured to said end portions, each of said second-mentioned sheets, upon the re- removal of the sheet between the leaf portions of which it is normally positioned, being adapted to be superimposed upon the coated sheet positioned between the leaf portions of the succeeding uncoated sheet with its coated side engaging the impression-receiving side of said coated sheet.

In testimony whereof I affix my signature, in the presence of two witnesses.

THOMAS WILBERFORCE OLD.
